UNITED STATES PATENT OFFICE.

ARTHUR H. BOSWORTH, OF WICHITA, KANSAS.

CONTAINER FOR EYEBROW PENCILS AND THE LIKE.

Application filed April 21, 1925. Serial No. 24,799.

An object of my invention is to provide for articles of this character a convenient means of sliding the material outwardly to compensate for wear in use, without leaving 5 unprotected openings in the tube; another object is to eliminate unnecessary and expensive manufacturing and assembling operations.

In the drawings, Fig. 1 represents a view 10 of the tube and pencil with a portion cut away to show the assembly. Fig. 2 is a side view and Figure 3 is an end view of the combined buffer and spring.

It is customary to market articles of this 15 character in tubes of various shapes, usually round or oval, and it is desirable to provide some means of sliding the pencil or material outwardly from the tube as it is worn away by use; this is usually accomplished by cutting 20 a slot in the tube, parallel with its length, inserting a metal slide within the tube as a receptacle for the pencil, and operating said slide by means of a screw projecting outside the slot, or other outside connection; this method is open to the objection 25 that an open slot is left through which foreign substances may enter and soilage of other articles take place through contact with the pencil. This method also requires 30 additional parts and expensive operations, both in manufacture and assembly. In the case of the larger tubes it is customary to provide a false bottom which may be pushed up to propel the stick, which is also a crude 35 and unsanitary arrangement.

In my invention I have made use of a seamless tube (1), closed at one end and provided with a cap for the open end, and as a means of propulsion of the pencil or stick 40 I have provided a weight (2), which may be of any suitable shape, size, or material, but is preferably a shot or ball as shown in the sketch, free to move within the tube and to act as a hammer to drive the pencil outwardly when the tube is shaken.

As the material of which these pencils is made is comparatively soft, it is essential for the successful working of this invention that a piece of harder material, which I 50 have called a buffer, (3) be interposed between the end of the pencil and the weight or hammer, so that the impact will not cause

the soft material to upset in form and jam in the tube; for the same reason the pencil should fit the tube rather loosely, making 55 it necessary to provide friction or tension between the pencil and the tube, sufficient to cause the pencil to remain in the position in which it may be placed in relation to the tube, while in use. I have accomplished this 60 by means of a spring interposed between the pencil and the walls of the tube, and in the particular form shown in the drawing (3 and 4) I have combined the functions of buffer and spring in one piece, but it is obvious 65 that other forms could be used, as, for instance, a short tube, sliding fit with the outer tube, deformed at points if necessary to make the desired resistance; or the springs could be made separately from the 70 buffer. The particular form which I have shown is in the shape of a U with sides slightly diverging toward the open end, the tips being bent inwardly. The amount of 75 tension, or resistance to change when once placed in the desired position can be easily regulated by varying the bulk, temper, and character of the material used, and by changing the angle of divergence. This particular form, with or without the increased 80 width in the central portion which forms the bottom of the U, as shown, has several advantages. It requires little material and can be made in one operation; before placing in the tube the pencil can be shoved into 85 the U and be seated against the bottom thereof without interference from diverging points; when this assembly is inserted into the tube the sides of the U are forced to converge, thus pressing the inturned ends into 90 the material of the pencil, making an inseparable assembly of the U and the pencil so long as they remain in the tube.

What I claim is,

1. A container for eye-brow pencils and the like, comprising a tube closed at one end, a U-shaped soft pencil-engaging combined buffer and clip in the closed portion of the tube, and a freely movable weight between the closed end of the tube and the combined 95 buffer and clip.
2. A container for eye-brow pencils and the like, comprising a tube closed at one end, a pencil engaging member frictionally en-

gageable with the inner wall of the tube having a blow-receiving portion, and a freely movable weight within the closed portion of the tube for impact with the blow-receiving portion of the pencil engaging member.

3. A container for eye-brow pencils and

the like, comprising a tube, closed at one end, a spring clip within the tube having pencil engaging means and a part to receive a blow, and a freely movable weight within the closed portion of the tube movable to exert a blow against the clip.

ARTHUR H. BOSWORTH.
